DISPENSING CONTAINER FOR LIQUIDS

Carl A. Gran, Arlington Heights, Ill., assignor to Magi-Pak Corporation, a corporation of Delaware

Filed July 1, 1963, Ser. No. 75,600

Term of patent 14 years

(Cl. D58—17)

FIG. 1

FIG. 7

FIG. 2

FIG. 6

FIG. 3

FIG. 4

FIG. 5

FIGURE 1 is a perspective view of a dispensing container for liquids showing my new design;

FIGURE 2 is a front elevational view thereof;

FIGURE 3 is a rear elevational view thereof;

FIGURE 4 is a side elevational view thereof;

FIGURE 5 is a bottom plan view thereof;

FIGURE 6 is a fragmentary detail cross-sectional view taken generally along line 6—6 of FIGURE 3; and

FIGURE 7 is a fragmentary detail view taken generally along line 7—7 of FIGURE 2.

I claim:

The ornamental design for a dispensing container for liquids, substantially as shown.
